CLAIM

The ornamental design for a phone case, as shown and described.

DESCRIPTION

FIG. 1 is a front perspective view of a phone case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, right, and top perspective view thereof showing the kickstand in an extended state; and,

FIG. 10 is a front, right, and bottom perspective view thereof showing the phone case in a horizontal orientation and the kickstand in an extended state.

The broken lines in FIG. 10 illustrate an environmental phone that forms no part of the claimed design.
